REFRIGERATION COMPRESSOR

Frank K. Smith and Curtis M. Brown, Tecumseh,
Mich.

Application February 3, 1937, Serial No. 123,886

8 Claims. (Cl. 230—206)

This invention relates to compressors especially adapted for use in electric refrigeration systems, and it has particular reference to the provision of an improved compressor which, while adequately and fully lubricated at all times, does not effect an excessive commingling of the lubricating oil with the refrigerant.

As is well understood in the art, a typical electric refrigeration system includes a compressor for compressing refrigerant vapors, a condenser connected to the discharge side of the compressor to cool and liquify the compressed refrigerant, an evaporator or expansion coil in which the liquid refrigerant is vaporized with the absorption of heat, and a return or suction line leading from evaporator to compressor inlet to effect the recirculation of the refrigerant. Refrigerants now in common use, particularly in the so-called small units, have the property of mixing, either by process of suspension or solution, with the oil used to lubricate the compressor, with the result that oil tends to accumulate in the expansion coils, and interfere with satisfactory operation.

The commingling of refrigerant and oil, which cannot be avoided altogether, since the compressor must be lubricated, has heretofore been partially offset by providing the compressor with what may be termed an overhead inlet, as distinguished from a crankcase inlet, for the admission of refrigerant vapors which are to be recompressed. The present invention, generally speaking, contemplates improvements in the overhead inlet type of compressor, to the end that its operation and functioning may be made more efficient, oil separation or limitation of commingling more positive, while insuring complete and adequate lubrication for all moving parts.

In achieving these general objects, the present invention proposes a number of novel features and improvements, which, for purposes of explanation, may be separately considered, although it will be apparent, as this description proceeds, that they are advantageously employed in conjunction with each other. It will also be understood that certain of these features may be independently employed, and may be applied to other types of compressors, without departing from the scope of the invention, as it is more fully set forth in the appended claims.

One feature of the invention will be found to reside in a novel and improved means for effecting the separation of incidental quantities of oil which are returned to the compressor with refrigerant vapors. Other features of novelty reside in the provision of means for effectively lu-

bricating the various working parts of the compressor, such as the main shaft seals, bearings, and piston and cylinder wall, without excessive injections of oil into the compressed refrigerant. Still another feature of the invention is the provision of improved means for imparting to the piston and connecting rod assembly a high degree of dynamic balance and ease of manufacture. Other and further features of the invention will be pointed out as this specification proceeds with a discussion of a typical embodiment, illustrated in the accompanying drawings, wherein:

Fig. 1 is a front elevation of the compressor, with a portion of the crankcase and associated structure shown in section;

Fig. 2 is an enlarged section on the line 2—2 of Fig. 1, showing the sealing ring formation;

Fig. 3 is a slightly enlarged section on the line 3—3 of Fig. 1;

Fig. 4 is a fragmentary section on the line 4—4 of Fig. 3;

Fig. 5 is a fragmentary section on the line 5—5 of Fig. 3, showing the oil pump impeller arm;

Fig. 6 is an enlarged fragmentary sectional view showing the positioning of the oil grooves in the piston, and the piston disposed at the top of its stroke in the cylinder;

Fig. 7 is a section on the line 7—7 of Fig. 1, with the upper portions of the compressor shown in elevation; and

Fig. 8 is a section on the line 8—8 of Fig. 3, showing more fully the disposition of the reservoir groove formed in the cylinder.

The compressor of the present invention is illustrated in the drawings as being of a single cylinder type having a cylinder block 10 integrally connected to a crankcase 11, although it will be understood that the novel features hereof may also be applied to multiple cylinder compressors. The crank case 11 is formed with aligned bearings 12 and 13, receiving a drive shaft 14, to which is keyed or otherwise secured an eccentric 15. A connecting rod 16 is formed at its lower end with a strap 17 disposed about the eccentric 15, and with a small end bearing 18 at its opposite end which receives a wrist pin 19, projecting into suitable bearings formed in a piston 21. Rotation of the shaft 14 therefore serves to reciprocate the piston 21 in the cylinder bore 22.

A cylinder head 23 is disposed on the upper end of the block 10 and it here comprises a two part structure including a head casting 24 and an interposed valve plate 25, both secured to

the block 10 by bolts 26. The valve plate 25 is provided with inlet and outlet valves 27 and 28, respectively disposed to cover inlet and outlet ports 29 and 31, which in turn are in fluid communication with inlet and outlet chambers 32 and 33 formed in the head casting 24 by a diametrically disposed partition wall 34.

The inlet and outlet chambers 32 and 33 are in turn connected, by registering orifices 37 and 10 38 formed in the valve plate 25, to inlet and outlet passages 35 and 36 formed vertically in the block 10. Laterally disposed holes 39 and 41 are formed in the wall of the block 10 to intercept the passages 35 and 36 respectively, and thus provide means for connecting the compressor to the evaporator suction line and condenser of the refrigeration system (not illustrated), to which it is assumed that the invention is applied.

It will be observed that the inlet passage 35 20 is in fluid communication with the crankcase 11 through a drilled oil escape opening 42 of relatively small diameter; it being intended that refrigerant and oil, entering the compressor through the opening 39, will be appreciably separated in the passage 35. The refrigerant may flow through the described passages into the cylinder bore 22 during the downward movement 25 of the piston 21, while compressed refrigerant may be discharged through the opening 41 during 30 movement in the opposite direction.

Disposed in the lower portion of the inlet passage 35, and above the opening 42, is a baffle member 45. The member 45 is in the form of an inverted cup having an external annular flange 46 35 adapted to fit snugly in the bore 35, with the cylindrical wall of the cup having a clearance from the bore to provide an annular well 47. It will be observed that the wall and upper end of the cup are imperforate, except for the provision of two holes, one of which, designated by 40 the reference numeral 48, is disposed at the bottom of the well and is of relatively small diameter. The other hole 49 is disposed adjacent the top of the well, and is of relatively large diameter, for 45 a purpose which will presently be explained.

A wire screen or cup 51 is disposed at the upper end of the passage 35, and it protects the compressor from dirt ingress and also serves to provide a means for effecting additional separation of 50 oil from the incoming refrigerant. The head casting 24 is further formed with a depending baffle wall 52 located in the refrigerant vapor path, and the inlet opening 29 receives a pipe 53 also serving to eliminate oil globules from the 55 refrigerant. All of these elements cooperate to reduce the quantity of oil which may enter the cylinder 22, and it will be apparent that, as the oil is separated, it flows down the passage 35, collects in the well 47, and may flow through the 60 holes 48 and 49 into the crankcase 11, through the opening 42.

The reason for making the holes 48 and 49 of different size will now be explained in accordance with our understanding of the principle involved. When the machine is operating, a condition of pressure pulsation and liquid surge is set up in the crankcase 11, due to the movement of the parts and the changes in volume. This action tends to eject oil through the opening 42, in a direction just reverse to that above described, and such reverse flow obviously is not wanted. The cup 45, together with the limited size of the hole 42, minimizes ejection of oil into the 70 passage 35, but might not, in the absence of 75

additional improvements, serve to prevent some reverse flow under all operating conditions.

The size of the parts is intended to be such that the amount of oil collecting in the well 47, for say each cycle of operation, is not enough to 5 fill the well to a point above the opening 49. This opening may therefore be regarded as a breather hole, and to the extent that gas compression occurs in the crankcase, the breather hole provides for reduction of such pressures as are developed, 10 thereby making for smooth operation. The hole 49 is also sufficiently large that, even if it should be submerged below the level of the oil in the well 47, gravity flow of the oil in one direction, and gas in the other, may take place. A suitable size 15 for such opening, in machines of the type herein illustrated, has been found to be about one-eighth of an inch diameter.

The hole 48, however, is made of such size that, 20 having in mind the operating conditions, it functions in accordance with the laws of fluid flow through a small orifice of negligible length. That is to say, when there is a surge from the crankcase toward the passage 35, the pressures on opposite sides of the orifice 48 are, or may be, substantially equalized, and hence no appreciable flow of oil will take place, because the orifice is 25 too small to admit of free flow under the force of gravity alone. When there is a pressure differential across the orifice 48, caused by a reduction 30 in pressure in the crankcase, oil in the well 47 may drain through the opening 48, under the influence of such pressure. A suitable diameter 35 for this orifice has been found to be one-sixteenth of an inch.

It will be seen that the orifice 48 thus serves as a drain and a check valve requiring no moving parts, while the opening 49 serves as a drain when required, and a breather hole under all operating conditions. Conjointly, and in cooperation 40 with the other elements of the machine, these apertures therefore serve to remove oil from the incoming vapors, and prevent the discharge of crankcase oil into the refrigerant which is to be compressed.

The lubrication of the compressor is accomplished by means associated with the drive shaft assembly acting on the oil contained in the crankcase 11. The bearing 12 is provided with oil inlet holes 55 which are supplied with lubricant splashed thereinto during operation. It will be noted that the bearing 12 is both a radial and thrust bearing, and the shaft 14 terminates therein, abutting the end thrust member 56. The bearing 13 is also provided with an oil hole 57 55 which communicates with a longitudinal slot 58 formed in the shaft 14, and also a seal chamber 59.

The seal chamber 59, through which extends the projecting end of the shaft 14, is closed on 60 the outer end by a cap plate 61, held in place by bolts 62. The chamber 59 receives a seal unit comprising an end plate 63 clamped between the cap 61 and the end of the crankcase 11, and a sealing ring 64 connected to the plate 63 by an 65 expandible bellows 65. The sealing ring 64 is urged toward a shoulder 66 formed on the shaft 14 by a spring 67.

The ring 64 is formed with an annular projecting portion 68 abutting the shoulder 66 to provide 70 a gas tight lapped joint, thereby preventing leakage of oil and refrigerant from the crankcase 11. It will, of course, be understood that the cavity formed between the inner face of the ring 64, the shoulder 66, and the peripheral surface of 75

the projecting portion 68 receives oil from the bearing hole 57. Heretofore, it has been endeavored to make a very tight joint in packless compressor seals, but when a sufficiently tight joint was obtained, as by lapping the contacting and relatively movable parts, no oil film could be developed therebetween, with the result that the carefully made joint would be burned out, thus leading to the destruction of the seal.

Accordingly, the present invention provides the projecting annular portion 68 with a plane shoulder-contacting face, and non-concentric portions on the outer peripheral surface, so that, as the shaft rotates, portions of the contacted shoulder are exposed to admit a film of oil. As best shown in Fig. 2, this effect is herein obtained by providing the annular peripheral surface 69 with flattened portions 71 which expose segments of the shoulder during operation. The efficacy of the seal is thereby maintained, and the cause of burning out is eliminated.

As hereinabove noted, the portion of the shaft 14 disposed between the bearings 12 and 13 receives an eccentric 15. One face of the eccentric 25 is formed with an integral counterweight 16, while the other face is formed with a projecting hub 16. It will be noted that the hub is both radially and axially slotted, as indicated by the reference numerals 77 and 78, to form a resilient 30 sector 79. The lower surface 81 of the hub 16 is cylindrical, and is adapted to receive a removable counterweight 82, which is secured thereto by bolts 83 extending vertically through the partially weakened sector 79. The bolts also secure 35 a sheet metal oil slinger 84 to the upper portion of the hub 16.

The removable counterweight is provided so that the strap 17 of the connecting rod 16 may be readily applied to the eccentric 15, by movement over the hub 16. After such assembly is effected, the counterweight 82 is brought into contact with the surface 81, and is loosely secured by insertion of the bolts 83. The entire eccentric, counterweight, and piston assembly is then inserted through the bottom of the crankcase 11, and the shaft 14 is pushed through the eccentric and hub into the bearing 12. The bolts 83 are thereupon tightened to clamp the eccentric to the shaft, and, by virtue of the structure provided, the resilient portion 79 may yield to such strains as are imposed, thereby taking up the stresses without distortion of the eccentric 15 itself. Upon operation of the compressor, the counterweights and oil splasher 84 serve to deliver adequate quantities of lubricant to the bearings 12 and 13 and the sealing ring 64, thereby preventing excessive wear on these parts.

The lubrication of the wrist pin bearing 18, and also the lubrication of the strap bearing 17, is accomplished by means of an oil pump formed on the eccentric 15. As best shown in Figs. 3, 4, and 5, the eccentric is formed with a laterally projecting lug 91 provided with an angularly drilled hole 92 communicating with a smaller hole 65 93 which extends through the rim of the eccentric 15 at the mid part thereof. The connecting rod 16 is formed with an axially drilled hole 94 leading from the strap 11 to the wrist pin bearing 18. The strap bearing is formed with grooves 70 or oil pockets 95 located on opposite sides of the lower end of the hole 94. Oil delivered through the hole 92 will, therefore, as the connecting rod reciprocates, find its way into the pockets 95, and will thus be delivered to the bearing 18.

Since the bore 92 is angularly disposed with

respect to the radius and tangent taken through the end of the hole 93, oil entering the bore 92 during periods of immersion in the crankcase will be forced, by centrifugal action, toward the hole 93 as the eccentric rotates about the center of the shaft 14. The force resulting from the rotation of the oil in the bore 92 therefore drives such oil, when registry is obtained between the hole 93 and the pocket 95, into the pocket and thence up the hole 94 into the wrist pin bearing. While the hole 93 is out of registry with the pocket 95, centrifugal force acting on the oil tends to force the oil out against the surface of the strap 11, thereby providing continuous lubrication for the lower bearing as well.

Another portion of the compressor requiring adequate lubrication is the surface of the cylinder 22, which is contacted by the piston 21. From what has been heretofore set forth, it will be apparent that negligible quantities of oil are present in the gas undergoing compression, and accordingly the lubrication of these surfaces is effected from the lower, or crankcase end, of the machine. Briefly stated, the lower end of the piston is made to convey oil up to the cylinder 25 wall, from whence the oil is disseminated in such manner as to lubricate the entire surface.

Referring to Figs. 3, 6, and 8, it will be observed that the piston 21 is formed adjacent its lower extremity with a groove 101 of angular formation, a second similar groove 102 disposed thereabove, and a pair of semi-cylindrical grooves 103 and 104 disposed at still higher points. In Fig. 3, the piston 21 is shown at the lower end of its stroke, while in Fig. 6, the piston is shown, 35 on a larger scale, as disposed at the upper extremity of its stroke.

While a very slight clearance, of say two to four ten-thousandths of an inch, is provided between the main body of the piston and cylinder 40 wall, the lower portion of the piston, particularly below the groove 102, is provided with a greater and progressively increasing clearance, thereby forming, in section, a tapered clearance notch 105 whose maximum width may be of the order 45 of say three thousandths of an inch, or appreciably more than the normal running clearance.

The upper end of the piston 21 is also formed with a head band 106 of reduced diameter which terminates in a groove 107, otherwise similar to 50 the grooves 103 and 104, thereby providing a second pocket 108 between the upper end of the piston and the cylinder wall 22. A pair of circumferential grooves 109 are formed in the cylinder wall 22, being interrupted to provide a continuous bearing surface in the cylinder bore for the positioning buttons 111 of the wrist pin 19, as shown in Fig. 8. The relation of the grooves formed in the piston 21 to the location of the grooves 109 is such that the groove 102 is aligned 60 with the grooves 109 when the piston is at the upper end of the stroke (Fig. 6), and the upper groove 107 is just barely aligned with the grooves 109 when the piston is at the lower end of the stroke (Fig. 3).

The mode of lubrication through the action of these various grooves may be understood by assuming that the piston 21 is at the lower end of the stroke, as shown in Fig. 3. The splashing action caused by the counterweights and associated moving parts throws oil into the groove 101, and, due to the viscosity of the oil and the angular formation of the groove, the oil will remain in place as the piston moves upward. When the piston is in the position shown in Fig. 6, the oil in 70

the groove 101, in endeavoring to run out, contacts the lower portion of the cylinder wall 22, and spreads thereover due to natural surface tension action. By this time, the piston is again 5 moving down, and, due to the wedge-like formation of the clearance opening 105, excess quantities of oil on the cylinder wall are squeezed through the normal clearance opening, and thence into the groove 102, which during such 10 period is spaced from the grooves 109. On the next upward stroke, the oil so conveyed to the piston groove 102 is elevated to lubricate a new portion of the cylinder wall, and the excess is, at the top of the stroke, deposited in the grooves 15 109, which thereupon become reservoirs for oil. These reservoirs are replenished as required, as operation continues, by a repetition of the foregoing steps.

Assuming the grooves 109 to be filled, it will be 20 observed that when the piston is at the lower end of the stroke, the upper groove 107 is in registry therewith, to receive a charge of oil, and, as the piston moves upward, the grooves 104 and 103 also receive oil for lubrication of the cylinder 25 wall. Each upper piston groove thereupon serves to convey oil from the reservoirs 109 to the cylinder wall, thus maintaining adequate lubrication at all times.

As the piston 21 moves upward, some scraping 30 action will occur, causing some of the deposited oil to flow into the pocket 108. If this pocket were not provided, there would be a possibility of excessive expansion of the piston over the head portion, with its attendant disadvantages. Additionally, the pocket catches and retains those 35 quantities of oil which otherwise would be scraped off into the cylinder for commingling with the refrigerant undergoing compression.

In practical use of the invention, it has been 40 found that compressors made in accordance herewith have been highly efficient, smooth in operation, practically noiseless or free from "knock", and so adequately lubricated at all running parts as to eliminate many of the difficulties heretofore encountered in this type of service. While it 45 has been found that the compressor is fully lubricated at all times, it has also been observed that very little oil is carried over into the condenser and expansion coils, thereby permitting such 50 parts of the system to operate at a higher efficiency. It will, of course, be understood that some minute quantities of oil will remain entrapped or dissolved in the refrigerant, but such amounts are readily returned, and are separated 55 as they enter the compressor to prevent accumulation of oil in the refrigerant.

It will be understood that while, for the purpose of presenting to those skilled in the art the best mode now known to us to apply the principles of the invention to practical use, references 60 have been made to the specific formation, relative locations, and dimensions of parts, it is not intended to restrict the invention to such details as stated, but to encompass within the scope 65 hereof all such modifications, variations, and adaptations as are within the context of the following claims.

We claim:

1. The combination with a compressor having 70 a crankcase, a cylinder block, and a head for the cylinder block, an inlet chamber formed in the head, a passage formed in the block and communicating with the chamber, of an oil drain extending between the passage and the crankcase, and 75 an inverted cup disposed in the passage and posi-

tioned over said drain, said inverted cup being formed with an aperture in the side wall thereof.

2. The combination with a compressor having a crankcase, a cylinder block, a head for the cylinder block, an inlet chamber formed in the head, 5 and a passage communicating with said chamber formed in the block, of a drain hole formed at one end of said passage and connecting the passage with the crankcase, an inverted cup disposed over said drain and spaced from the wall of said passage to provide a well, and a plurality of apertures formed in the cup and positioned at different elevations with respect to said well. 10

3. The combination with a compressor having a crankcase, a cylinder block, and a head for the block formed with an inlet chamber, an inlet passage formed in the block and communicating at one end with the inlet chamber, of a drain hole formed in the opposite end of said passage and connecting said end with the crankcase, an inverted cup disposed over said drain and spaced from the wall of said passage to form a well, and apertures formed in the cup at progressively higher points with respect to said well, the lowermost of said apertures being of the smallest diameter for the purpose described. 15

4. That improvement in refrigeration compressors of the type having a crankcase, a cylinder block formed with a passage in the wall thereof, and a cylinder head having an input 30 chamber in communication with the passage and the cylinder, comprising a drain hole of less diameter than the passage formed at one end of said passage and communicating with the crankcase, a cup member positioned over said drain and in and spaced from the wall of said passage to provide a well for the accumulation of oil, an orifice of small diameter formed in the wall of the cup adjacent the bottom of the well, said orifice being of such diameter as to resist the flow 35 of oil therethrough in either direction during periods of surge from the crankcase toward said passage, and a breather opening formed in the cup adjacent the top of said well. 40

5. The combination with a compressor having a crankcase, a shaft in the crankcase, a cylinder block, and a piston reciprocably mounted in the cylinder block, an eccentric mounted on the shaft, a connecting rod formed with bearings at each end thereof respectively encircling the eccentric and a wrist pin forming a connection with the piston, said connecting rod being further formed with an axial hole extending between said bearing, of a laterally projecting boss formed on one face of the eccentric and extending from the periphery thereof and at an angle to a radius or tangent drawn through said portion of the periphery, said boss being formed with a bore extending from the outer end thereof through said periphery, whereby, upon revolution of said shaft and eccentric, oil entering the outer end of said bore will be centrifugally forced between said eccentric and bearing and through said axial hole to lubricate said wrist pin. 55

6. The combination with a compressor having a crankcase adapted to contain lubricant, a shaft mounted in the crankcase, a cylinder block, a piston formed with a wrist pin mounted in the cylinder block head, an eccentric secured to 70 the shaft, a connecting rod formed with bearings at each end thereof respectively encircling the eccentric and wrist pin, of means for lubricating said bearings with lubricant contained in said crankcase, said means comprising a boss laterally 75

extending from one face of the eccentric at a portion thereof remote from the center of the shaft, said boss extending from the periphery of said eccentric in an angular direction with respect to a radius and tangent drawn through the boss and periphery, said boss being formed with a bore extending from the outer end thereof to and through the periphery of the eccentric, an axial hole formed in the connecting rod and connecting the bearings formed at either end thereof, and a pocket portion communicating with said hole formed in the bearing of the rod engaging the eccentric.

7. The combination with a compressor having a crankcase, a cylinder block, and a head for the cylinder block, an inlet chamber formed in the head, a cylindrical passage formed in the block and communicating with the chamber, of an oil drain extending coaxially between one end of the passage and the crankcase, and an inverted cylindrical cup disposed in concentric spaced relation to the wall of the cylindrical passage to form a well, said cup being secured in said passage over said drain, said cup being formed with a drain aperture in the side wall thereof.

8. In a compressor having a cylinder wall, a crankcase adapted to contain lubricant, and a piston disposed in said wall for reciprocatory movement toward and away from the crankcase, means for lubricating the cylinder wall and piston comprising the formation of a tapered portion on the crankcase end of the piston, oil receiving and transmitting grooves formed respectively at the lower and upper end of said tapered portion, the upper end of said piston being of reduced diameter to provide a clearance and oil retaining pocket, a circumferential groove in the piston at the lower end of said pocket, other oil grooves formed in the piston between said pocket and transmitting groove, and an oil reservoir groove formed in the cylinder wall and so positioned with respect to the length and the stroke of the piston as to be in registry with the lower end of said pocket at one extremity of piston movement, and in registry with the transmitting groove at the opposite extremity of piston movement and with said other oil grooves at intermediate positions of the piston.
